ILLUMINABLE CHRISTMAS DECORATION

Otto Kadmon and Alice Kadmon, both of 144-37
76th Road, Flushing, N.Y. 11367

Filed Dec. 16, 1968, Ser. No. 15,034

Term of patent 7 years

Int. Cl. D11—05

U.S. Cl. D29—1

FIG. 2 is a side elevational view of one of the similar figures looking in the direction of the arrows 2—2 of FIG. 1;

FIG. 3 is a rear elevational view of the figure shown in FIG. 2 looking in the direction of the arrows 3—3 of FIG. 2; and

FIG. 4 is a top plan view thereof looking in the direction of the arrows 4—4 of FIG. 3.

We claim:

The ornamental design for an illuminable Christmas decoration, substantially as shown.
